UNITED STATES PATENT OFFICE.

WILLIAM CLAIBORNE HALL, OF CAYCE, KENTUCKY.

TRACE-HOOK.

SPECIFICATION forming part of Letters Patent No. 624,647, dated May 9, 1899.

Application filed February 21, 1899. Serial No. 706,341. (No model.)

To all whom it may concern:

Be it known that I, WILLIAM CLAIBORNE HALL, a citizen of the United States, residing at Cayce, in the county of Fulton and State 5 of Kentucky, have invented certain new and useful Improvements in Trace-Hooks; and I do declare the following to be a full, clear, and exact description of the invention, such as will enable others skilled in the art to which 10 it appertains to make and use the same.

My invention relates to certain novel improvements in trace-hooks, and more particularly to that class in which the draft of the animal on the trace or tug is taken up by a 15 spring; and the object is to improve and simplify the construction and increase the convenience, efficiency, and durability of the device.

To this end the invention consists in the 20 construction, combination, and arrangement of the several parts of the device, as will be hereinafter more fully described, and particularly pointed out in the claim.

In the accompanying drawings the same 25 reference characters indicate the same parts of the invention.

Figure 1 is a perspective view of my improved trace-hook. Fig. 2 is a longitudinal section of the same. Fig. 3 is a transverse 30 section.

1 denotes an approximately cylindrical box or casing secured to the shaft by the clips 3. This casing is formed with integral end walls 4, between which is formed a longitudinal pocket, the bottom of which is provided 35 with a longitudinal V-shaped groove 5. This pocket is provided with a removable cover 6, which is held in place by the clips 3 3. The forward end wall 4 is formed with an orifice 40 to receive the rod 7, the forward end of which terminates in the trace-hook 8, and its rear end carries an adjustable collar 9, formed with a radial V-shaped toe 10, which has a sliding engagement with the groove 5 to prevent 45 the trace-hook from turning on its axis,

but which will not interfere with its longitudinal movement in the casing.

12 denotes a spiral spring encompassing the rod 7 between the fixed wall 4 and the collar 9, the tension of the spring being taken up 50 by the animal, and thus preventing any jar to the animal or the vehicle.

Of course it will be understood that a device of this character dispenses with the usual whiffletree and in addition to this feature 55 possesses many advantages which will be appreciated and understood by those familiar with a one-horse vehicle.

The accompanying drawings show my invention in the best form now known to me; 60 but minor changes in the details might be made within the skill of a good mechanic without departing from the spirit of my invention as set forth in the claim at the end of this specification.

Having thus fully described my invention, what I claim, and desire to secure by Letters Patent of the United States, is—

A spring-draft trace-hook comprising a casing consisting of a box 1, provided with integral end walls 4 forming a longitudinal pocket, the bottom of which is provided with a longitudinal groove 5, and a removable cover 6 which entirely closes the pocket and is held in place by clips 3 3, the forward end wall of 70 said box being provided with an aperture; in combination with the longitudinal spring-actuated rod provided with the trace-hook, the collar adjustably secured to the rear end of 75 said rod by a set-screw provided with a toe 80 which projects into said groove, substantially as and for the purpose set forth.

In testimony whereof I have hereunto set my hand in presence of two subscribing witnesses.

WILLIAM CLAIBORNE HALL.

Witnesses:

SAM EDGER HALL,
WALTER MINUS.
